FRANK E. MAYOL, OF YOUNGSTOWN, OHIO.

LEAD PENCIL.

Application filed May 14, 1927. Serial No. 191,446.

This invention relates to lead pencils.

The primary object of the invention is to provide a writing shaft comprising a plurality of spaced "leads" connected by tubular sectional parts for use in connection with mechanical pencils, in order that a sharp pointed lead may be available at any time desired by the user.

A more specific object of the invention 10 comprises the idea of forming leads with a decidedly tapered point and connecting these leads together by interposing tubular sections of material such as paper, which tubular sections are detachably secured to the leads to expose the point of an unused lead when desirable.

Another object of the invention is to extend the tubular sections downwardly over a portion of the lead for the purpose of reinforcing or strengthening the lead at the point where the leads ordinarily break near the metallic containers of the mechanical feeding apparatus.

Numerous other objects of the invention 20 will be apparent from the following drawings, in which

Fig. 1 is an elevation of the pencil,

Fig. 2 is a longitudinal sectional view, and

Fig. 3 is a detailed view partly in section.

Automatic or mechanical pencils now in 30 vogue are usually equipped with a thick lead or a thin lead. Thick lead affords no writing point whatsoever and is entirely unsuitable for general use. The conventional "thin" lead, however, is extremely fragile and continually breaks during the normal pressure to which the average user of a pencil subjects the same when writing.

As will be apparent from the following 40 description, my invention comprehends the provision of a number of relatively thick leads provided with tapered points, together with interconnecting devices for such leads which are so constructed that a fresh pointed lead section may be exposed for writing purposes when needed.

With respect now to the drawings, 1 designates what I term herein as a "writing" shaft, comprising a plurality of leads connected together by hollow tubular sections 2 which are detachably secured to the leads in a manner to be hereinafter described. 50 3 designates the leads I employ which are sharply tapered as at 4, and provided with 55 a circumferential shoulder 5, a shank 6, and

a circumferential recess 7 provided under the lower portion of the shoulder 5. The tubular sections 2 are preferably constructed of paper, and are provided with an inturned flange 8 at their upper ends for engaging the 60 recess 7. The shanks 5 of the various leads fit within the confines of the tubular sections 2, as clearly shown in the drawing. The shoulders 5 space the adjacent ends of the sections 2 apart, which sections abuttingly 65 engage the shoulder.

In order to permit ready detachability of the section from a new lead when a fine point is desired, I preferably slit the sections as shown at 9 so that they may be spread apart 70 as shown in Fig. 2 to thereby disengage the section from the lower portion of the lead and render it available for use.

The lower portions of the tubular sections 2 surround the shank of the lead in such a 75 way that the lead is reinforced at the point where it frequently breaks off with the ordinary mechanical pencil, namely, against the side of the terminal portion of the metallic casing. The shank portions of the leads are 80 more or less permanently connected with the tubular sections 2, while the upper portions of such sections afford a free joint with the recesses formed in the leads by virtue of the slotted arrangement of the tubular sections. 85

It will be obvious to those skilled in the art that the writing shaft may be employed with or without a mechanical pencil of the automatic type, it being necessary in the latter case to merely so place or treat the shoulders of the leads that they will not soil the hands of the user.

The term "lead" as used herein is intended to embrace crayons or other writing substances, and I do not intend to limit the following claims to the literal meaning of the term "lead".

Having thus described my invention, what I claim is:

1. A writing shaft adapted for mechanical lead pencils, comprising a multiplicity of lead sections, tubular members connecting said lead sections together, said tubular members detachably engaging the leads to expose a new pointed lead when desired. 100

2. A writing shaft comprising a plurality of spaced leads, tubular members connecting and spacing said leads apart, each of said leads having a pointed end, recesses formed within said leads, flanges on said members 105 110

engaging the recesses, said flanges being slotted to permit spreading action thereof to disengage the sections from the lead.

3. A writing shaft for use in connection with automatic pencils comprising a multiplicity of superimposed leads and connecting tubular members detachably securing said leads together, shoulders on the leads fitting within the confines of the lower portions of the tubular members, said members being disengageable from the lower portions of the leads to thereby expose a new lead point when desired.

4. A writing shaft comprising a plurality of superposed, spaced apart leads, said leads being provided with a shank, shoulder, and recesses, tubular members detachably securing said leads together, the lower portions of the tubular members tightly receiving the shanks, and the upper portions of said tubular members being provided with inturned flanges fitting said recesses and abuttingly engaging the lower portions of the said shoulders of the leads. 15 20

In testimony whereof I affix my signature.

FRANK E. MAYOL.
